SIGN STRUCTURE

Robert J. Roston, New York, N.Y., assignor to
City of Anaheim

Filed May 26, 1970, Ser. No. 23,161

Term of patent 14 years

Int. Cl. D20--03

U.S. Cl. D96—12

FIG. 1.

FIG. 2.

FIG. 3.

FIG. 4.

FIG. 1 is a front-elevational view of a sign structure embodying the new design of my invention;

FIG. 2 is a rear-elevational view thereof;

FIG. 3 is a side-elevational view thereof; and

FIG. 4 is a top plan view thereof.

The side view of the sign structure illustrated which is not shown in the drawing is a mirror image of the side view shown.

I claim:

The ornamental design for a sign structure, substantially as shown and described.
